A. L. HOLLEY.
Making Bessemer Steel.

No. 106,162.

Patented Aug. 9, 1870.

UNITED STATES PATENT OFFICE.

ALEXANDER L. HOLLEY, OF BROOKLYN, NEW YORK.

IMPROVEMENT IN APPARATUS FOR THE MANUFACTURE OF BESSEMER STEEL.

Specification forming part of Letters Patent No. **106,162**, dated August 9, 1870.

To all whom it may concern:

Be it known that I, ALEXANDER L. HOLLEY, of the city of Brooklyn, county of Kings, and State of New York, have invented certain new and useful Improvements in Apparatus for Making Bessemer Steel, and also an improved method of setting the bottoms of converters; and I hereby declare that the following is a full, clear, and exact description thereof, reference being had to the accompanying drawings.

This invention relates to an improved means for facilitating the repairs of the linings of the converters employed in the Bessemer or pneumatic process. The converter-bottom is generally known, and for the purposes of this specification will be considered, as the tuyeres, together with that part of the refractory lining of the converter in which the tuyeres are set. These bottoms are generally so much burned or worn away after five to eight heats as to require renewal. This renewal has heretofore been done in the following ways: The tuyeres have been knocked out of the mass of ganister in which they were set, new tuyeres have been placed in the old holes, and the lining has been made around them by pouring into the mouth of the converter semi-fluid ganister and water, called "slurry," which does not make a sound or safe bottom. Or the whole bottom has been withdrawn from the converter, and a duplicate bottom, previously rammed up and dried, has been inserted into the large ragged hole thus left in the lower part of the converter, and the large annular space between the new bottom and the sides of the hole in the lining of the converter has been filled by pouring slurry into it; but the slurry in this case also cannot be relied on to set soundly, and often gives way, allowing the metal to run out. Or, instead of using slurry in the cases above named, the lining is sometimes made good around the tuyeres or around the bottom by workmen getting into the converter and ramming it by hand; but as this requires waiting twelve to twenty-four hours for the vessel to cool sufficiently to enter it with safety, much time is lost and the product of the works is seriously diminished.

There are other modifications of the practice I have described, but none that make an absolutely solid lining without great waste of time.

My improvement consists in the method and arrangement herein described, and in the means and apparatus for making a sound joint between the removable bottom and the lining of a converter.

To enable others to construct and use this invention, I have shown one common and convenient application of it in the drawings which form a part of this specification, and in which the same letters refer to like parts.

Figures 1 and 2 are sections of the lower part of a converter, of which A is the iron shell, B the refractory lining, and E the ring, to which the tuyere-box H is fastened by the cotter-bolts W. The tuyere-box H receives the blast from the blowing-engine through the pipe K, and distributes it to the tuyeres D in the usual manner. When a bottom requires replacing the tuyere-box is removed, and the bottom C, which is attached to the tuyere-box, is thus pulled out of the converter, leaving a ragged opening in the converter-lining, as shown by the lines S S S S, Fig. 2. A duplicate tuyere box and bottom (shown in section in Fig. 5) is then attached to the converter, as shown at Fig. 2, and the annular space between the bottom and the lining is rammed with the refractory material U V, by men working from the outside of the converter, by means of the rammers a e. To enable the ramming from the outside to be done, I prefer to make the relative diameters of the tuyere-box and the opening in the lower part of the shell of the converter such that after the tuyere-box is attached to the converter it shall not entirely close this opening, but shall permit a portion of the opening (which portion constitutes the annular space above referred to) to be exposed, so that it can be filled by ramming, as hereinafter described; and I construct the tuyere-box in such manner that, instead of the usual provisions for fastening it to the converter by means of flanges or otherwise, as are well known, I provide it with the brackets R, ter-

minating in the thimbles F, through which thimbles the cotter-bolts W, which are secured in the ring E of the converter, may pass and attach the tuyere-box to the converter. It will be seen that the use of these brackets leaves open spaces between each two of them, and through these spaces the material to be rammed into the annular space and the tools for molding and ramming may be inserted and worked. I prefer to make these openings three to four inches wide and eight to twelve inches long.

The tuyere-box is shown in plan at Fig. 7, and is shown reversed and attached to the shell of the vessel in plan at Fig. 6.

After a new bottom is inserted into the hole left in the converter by the removal of the old bottom, as shown at Fig. 2, the annular space between the bottom and the converter-lining may be readily filled with refractory material through the openings G. The manner in which I usually perform this filling is as follows: I turn the converter upon its side, so that the tuyere shall lie nearly horizontal. I form the refractory material (by preference two parts ground quartz or sandstone and one part ground fire-clay, the whole made slightly plastic by water) into cakes about the size of ordinary fire-bricks, and of suitable shape for insertion into the spaces they are to fill. I place one of these cakes in the extreme inner part of the annular space, pat it, and mold it sidewise (with the flat side of the rammer, as at V, Fig. 2) against the lining. I then insert another cake and mold it against the bottom C. I then insert a third cake of wedge form between the two others and press it firmly in to stop the hole. I then stop up another section of the annular space in the same way. The ring thus formed in the inside of the annular space soon sets, especially if the lining is red-hot from recent use, so that the converter can be turned bottom upward, and the remainder of the space can be filled by shoveling in ordinary lining material and ramming it. I prefer, however, to fill the whole annular space by the combined lateral molding and ramming described. The time occupied by this operation need not exceed forty-five minutes for a five-ton converter. When the annular space is thus stopped I sometimes turn the converter so that the tuyere-box is down, and pour in a few buckets of slurry to make the top of the newly-rammed part even and smooth; but this is not essential. When the annular space is rammed full, as at Y, Fig. 1, I usually place the iron covers O over the openings G, to prevent the material rammed in from crumbling and falling out. This material may be made stiff enough to stand without the covers; but I deem it safer to use them. These covers may be held in place by a simple cotter-bolt set in the ring E, as shown at Fig. 6.

Another means of carrying out my improvements which may be adopted, if desired, is

to provide suitable apertures, 222, through the shell of the converter, whereby the annular space may be exposed, so that it may be reached and rammed through these apertures, care being taken that they shall be arranged and located opposite the annular space and below the line of the upper surface of the new bottom when the latter is inserted into the converter. The ramming of the annular space may then be performed in the manner above set forth, or in any other suitable manner, and the material, after it has been rammed, may be covered and held in by suitable covers, 3, such as have been already described. After the bottom is thus set the converter should, if possible, be heated in the usual manner. If the converter has been in use immediately before setting the bottom, an hour's heating is sufficient; and, if necessary, the converter may be used immediately after the annular space is rammed.

I prefer a hydraulic lift under the converter to remove and insert the bottoms; but this may be done by a crane overhead, or in any convenient manner.

When a tuyere-box is removed from the converter the connection between the air-supply pipe L, Fig. 3, and the air-pipe K, that enters the tuyere-box, must be broken. In order that this may be done without removing any connections, and in order that the new tuyere-box may be readily put in communication with the pipe L, I prefer to use the simple stuffing-box and gland N shown by Figs. 3 and 4.

The duplicate bottoms (of which I prefer to have at least two for each converter) are made by inserting the tuyeres D through the top of the tuyere-box, placing the mold, Fig. 8, around them, and ramming the space inclosed by the mold with ganister or other refractory material in the usual manner. The bottoms may then be dried by being baked in ovens, or in any suitable manner.

I do not claim the use of duplicate bottoms in converters.

What I do claim, and desire to secure by Letters Patent, is—

1. The combination, with a converter, of a tuyere-box having such relation to the opening in the bottom of the shell of the converter that when the tuyere-box is attached to the converter a portion of the opening in the converter constituting the annular space above described shall be exposed, so that it can be filled by ramming from the outside of the converter, substantially as and for the purposes set forth.

2. The combination, with the tuyere-box, of two or more brackets having between them openings suitable to admit of ramming the annular space above described from the outside of the converter, in the manner and for the purposes set forth.

3. The herein-described arrangement in the lower portion of a converter of openings through

the shell thereof, located opposite the annular space and below the line of the upper surface of the new bottom, and adapted to enable the annular space to be filled by ramming from the outside of the converter, substantially in the manner described.

4. The herein-described method of filling the annular space by so exposing the same that it may be reached and rammed from the outside of the converter, substantially as and for the purposes made known.

5. The combination, with the shell of the converter, of the covers, as described, for the purpose of covering and holding in the rammed material, substantially as set forth.

A. L. HOLLEY.
